UNITED STATES PATENT OFFICE.

SAMUEL C. LANCASTER, OF JACKSON, TENNESSEE.

DUMPING-VEHICLE.

No. 808,991.

Specification of Letters Patent.

Patented Jan. 2, 1906.

Application filed January 18, 1905. Serial No. 241,673.

To all whom it may concern:

Be it known that I, SAMUEL C. LANCASTER, a resident of Jackson, in the county of Madison and State of Tennessee, have invented 5 certain new and useful Improvements in Dumping-Vehicles; and I do hereby declare the following to be a full, clear, and exact description of the invention, such as will enable others skilled in the art to which it appertains to make and use the same.

My invention relates to an improved dumping-vehicle, the object of the invention being to provide an improved two-wheel dumping-vehicle having a hopper-shaped body comprising 15 two half-sections hinged together at their upper ends and provide means for permitting the sections to separate for dumping the contents or to be drawn together.

A further object is to provide improved 20 means for changing the pitch of the wheels to ride flat on the roadway regardless of the curvature or pitch of the latter.

With these and other objects in view the invention consists in certain novel features 25 of construction and combinations and arrangements of parts, as will be more fully hereinafter described, and pointed out in the claims.

In the accompanying drawings, Figure 1 is 30 a view in side elevation, illustrating my improvements. Fig. 2 is a vertical section, and Fig. 3 is a plan view.

1 represents a frame comprising longitudinal angle-iron bars disposed parallel and located 35 a proper distance apart through the intermediate portions of their length and converging together at their ends. These bars 1 are connected by diagonal braces 2 with vertical bars 3, and the latter carry at their lower 40 ends axle-stubs 4, on which traction-wheels 5 are mounted. The upper ends of bars 3 are made with openings to receive a cross-rod 6, which latter projects at its ends beyond bars 3 and is screw-threaded to receive nuts 7, and 45 the nuts 7 are rounded to receive similarly-shaped enlargements on the bars 3 and form, in effect, ball-and-socket joints to permit the bars 3 to be adjusted, as will be hereinafter explained, to change the incline of the wheels 50 to suit the pitch of the road.

8 represents the vehicle-body, which is of the general hopper shape shown, comprising two half-sections hinged together at their upper meeting edges, and the cross-rod 6 serves 55 as the support for the body and hinge-pin to connect the half-section.

Bars 3 near their lower ends are made with openings to receive a rod 9, which passes between the half-sections and rests in notches therein. One end of the rod 9 has a head 60 against one bar 3 and the other end is screw-threaded to receive a nut 10. The connections between the upright bars 3 and the cross-rod 6 are made loose—in effect, as before explained, ball-and-socket joints. The 65 rod 9 is, as shown in Figs. 1 and 2, located a considerable distance below the rod 6, and when the nut 10 on one end of the rod 6 is turned the tendency will be to draw the uprights 3 toward each other, causing them to 70 turn on the ball-and-socket connection with the cross-rod 6, the draft-frame 1 being sufficiently yielding or elastic to permit such inward adjustment of the uprights 3. Thus it will be seen that by screwing the nut on the 75 rod 9 the uprights can be inclined inwardly and that the broad treads of the wheels will necessarily be caused to assume the same inclination and made to run flat on the road instead of running on their edges, and thus marking the road. It will therefore be seen that by adjusting the nut 10 the angle of inclination of the wheels can be varied to suit any pitch of road, and the rod 9 also serves as a 80 lateral strengthening-brace to the body-supporting bars or uprights 3.

One body-section provides mounting for a shaft 11, carrying drums at both sides of the body, and chains 12, secured to said drums, are passed around rollers or pulleys 13 on the 85 other body-section and then secured to the first-mentioned section at or near its lower end. A crank 14 is provided to turn shaft 11, wind the chain on the drums, and draw the body-sections tight together or permit 90 them to separate, and a ratchet-wheel 15 is located on the shaft and controlled by a dog 16. To effectually lock the sections together, a lever 17 may be pivotally secured at one 95 end to one section and has a shoulder near its other end to engage behind a shoulder on the other section and securely hold the sections together.

The vehicle may be used alone or in a train 100 with others and may have any form of coupling, shafts, or tongue, according to the use to which it is to be put.

The upright bars 3, axle-stubs 4, and connecting-bar 6 constitute a crank-axle, supporting the body between the wheels. By 110 constructing a vehicle as above explained great economy of space is secured not only in

the dimensions of the vehicle, but also in its use, as it can turn in its own length, and the draft is exceedingly light. Also the incline of the wheels can be changed to suit the pitch 5 of a road and instead of cutting into the road will act as rollers to evenly press the same.

A great many slight changes might be made in the general form and arrangement of the parts described without departing from my 10 invention, and hence I would have it understood that I do not restrict myself to the precise construction shown, but consider myself at liberty to make such slight changes and alterations as fairly fall within the spirit and 15 scope of my invention.

Having fully described my invention, what I claim as new, and desire to secure by Letters Patent, is—

1. A dumping-wagon comprising a frame 20 and two body - sections hinged together at their upper ends and supported within said frame, and a single wheel at each side of said frame.

2. A dumping-wagon comprising a sectional hopper-shaped body having its members hinged together at the top, a draft-frame, means for mounting said body-sections in said draft-frame and a single wheel at each side of said draft-frame.

3. A dumping-wagon comprising a draft-frame, a wheel at each side thereof, upright bars located centrally on said frame, and two body-sections hinged together at their upper 30 ends and supported coincident with said hinged connection by said upright bars.

4. A dumping-wagon comprising a draft-frame, axle - stubs projecting outwardly at each side of said frame, wheels on said axle-stubs, bars attached to the draft-frame adj- 40 cent to said axle-stubs and projecting upwardly, and a hopper-shaped body comprising two hinged members, disposed between said upright bars and supported from the upper ends thereof.

5. A dumping-wagon comprising a draft-frame, a single wheel at each side of the center thereof, a hopper-shaped body comprising two sections hinged together at their upper ends, means supporting said body at 50 their hinged upper ends, upon said draft-frame, means for normally locking said body-sections together and means for drawing the sections together.

6. The combination of a crank-axle, wheels 55 supporting the same, and a body comprising

two sections, each hinged upon and supported by said crank-axle between said wheels.

7. The combination of a crank-axle, wheels supporting the same, and a hopper-shaped body suspended from the axle, and comprising 60 two half-sections hinged together upon the axle.

8. The combination with a crank - axle, wheels supporting the same, and a body suspended from the axle, of means for adjusting 65 the axle to change the angle of inclination of the wheels.

9. The combination of a crank-axle comprising separable sections, wheels supporting said axle, a body suspended from the axle, 70 and a rod passed through upright sections of the crank-axle, and a nut screwed on said rod and adapted to adjust the axle-sections to change the angle of inclination of the wheels.

10. In a dumping-vehicle, the combination 75 with a horizontal open frame, of a crank-axle having its stubs projected out beyond the frame, wheels on said stubs, and a hopper-bottom suspended from the axle in the frame, and comprising two half-sections hinged together on the axle, means for drawing the sections together or permit them to separate, and means for locking them together.

11. A dumping-wagon comprising a frame, 80 wheels supporting said frame, a body supported by the frame, and means for adjusting the wheels to adapt them to the pitch of the road.

12. The combination with a body, a frame carrying the same, and wheels supporting 90 said frame and body, of means for inclining said wheels in opposite directions to adapt their treads to the pitch of the road to be traveled.

13. A dumping-wagon, comprising a draft-frame, uprights thereon, a body supported in said frame, axles projecting laterally from the lower ends of said uprights, wheels on said axles, and means for inclining the uprights to incline the treads of the wheels to 100 adapt them to the pitch of the road to be traveled.

In testimony whereof I have signed this specification in the presence of two subscribing witnesses.

SAMUEL C. LANCASTER.
